UNITED STATES PATENT OFFICE

CHARLES B. PAGE, OF EVANSTON, ILLINOIS, ASSIGNOR, BY MESNE ASSIGNMENTS, TO
THE G. W. DULANY TRUST, OF CHICAGO, ILLINOIS, A COMMON-LAW TRUST

FURNACE

Application filed June 21, 1929. Serial No. 372,605.

The present invention relates to improvements in furnaces, particularly furnaces using gaseous fuel and adapted for the heating of boilers and water heaters.

5 It is well known that artificial or natural gas burns with a blue flame when sufficient air for complete combustion is supplied. It is also known that when gas and air are mixed in the proper proportion previous 10 to delivery to the burners, the most efficient utilization of the heat generated can be obtained because there is then no excess air to be heated. Under the condition of properly premixed gas and air the flame is only 15 slightly luminous and therefore does not emit any appreciable amount of radiant energy.

Modern boiler design is based on the highest possible utilization of radiant energy, 20 and it is well known that the tremendous capacity of boilers of the internally fired type is due to the heat transfer capacity of the fire box—some 35 or 40% of the total heat being transferred by radiant energy.

25 The transfer of heat from a highly heated gas which is not luminous can only be accomplished by bringing the gas in contact with the surface to be heated. But if the rate of heat transfer is to be high, then the 30 gas must be brought rapidly in contact with the surface and quickly replaced by other hot gas as it cools. This requires a high velocity and turbulence of the gas.

The present invention has for its object 35 to provide a highly radiant fire box for gas fired furnaces and boilers.

Another object of this invention resides in the provision of novel means for creating a violent turbulence and mixture of gases 40 within a furnace.

Further objects and advantages will become apparent as the description proceeds.

In the accompanying drawings Fig. 1 is a vertical section through a boiler having 45 a furnace embodying features of my invention, and the section is taken along line 1—1 of Fig. 2.

Fig. 2 is a horizontal section taken through Fig. 1 along line 2—2.

50 While the invention is susceptible of vari-

ous modifications and alternative constructions, I have shown in the drawings and will herein describe in detail the preferred embodiment, but it is to be understood that I do not thereby intend to limit the invention 55 to the specific form disclosed, but intend to cover all modifications and alternative constructions falling within the spirit and scope of the invention as expressed in the appended claims.

Referring more particularly to the drawings, I have shown a vertical tubular boiler 10 mounted upon the furnace structure. The furnace structure is contained within a casing and in the present instance this casing 15 is made circular to conform to the shape of the water leg of the boiler used in illustrating the adaptability of this invention. In order to facilitate manufacture and ease of handling, the casing may be made up in any 20 number of desired sections. In the present instance the casing is shown as made up of four parts or sectors 11, 12, 13 and 14. In order to strengthen the vertical wall and provide means for fastening adjacent sectors together, each sector is provided at each 25 end with flanges 15. The adjacent sectors are held together by means of bolts 16 which pass through openings in the flanges.

Each sector is also provided with a top 30 flange 17 upon which the boiler is mounted. The bottom wall 18 of each sector has a step 19 at the inside edge which carries a circular center plate 20. The entire casing is mounted upon suitable supports 21.

In the present instance each sector has two indented flat surfaced recesses 22. There is an opening through each recess into which burners 23 are inserted at right angles to the flat surface of the recess. The burners are held in place by clamps 24 and bolts 25. The recesses and burners are positioned in such a manner that the burners are directed slightly upward and also at an angle 35 to radial lines from the center of the furnace, all burners being inclined in the same direction. In this way the gases are given an upward and circular motion.

The casing is lined with a heat insulating material 26 inside the side and bottom walls 40

and an inner lining of refractory material 27. This refractory lining at the side wall extends substantially above the top wall of the casing and into the inner shell of the boiler. In this way considerable extra surface for radiant heat is obtained. The heat insulating lining and the refractory lining have openings or tunnels for the burners. The burners do not extend completely through the tunnels in the refractory lining but end substantially within the inner end of the tunnel. This gives a very effective ignition surface for maintaining combustion of the fuel within the tunnel and results in almost complete combustion of the fuel within the tunnel, combustion being fully completed as the gases pass into the combustion chamber 28.

The burners are connected to a fuel manifold 29 by means of pipe connections 30 and this manifold receives fuel through an inlet connection 31. In the present instance this fuel comprises a mixture of gas and air in the proper proportions supplied under a pressure.

A pilot burner 32 is inserted through the side wall of one of the sectors. This pilot burner receives its supply of gas and air from a separate source than that which supplies the main burners.

The floor of the combustion chamber 28 is covered with lumps of refractory material 33 which may consist of broken up fire brick. This aids considerably in conserving some of the heat of the gases into radiant energy and further aids in the distribution of the radiant energy to the crown sheet 34 and fire box walls 35 of the boiler 10.

I claim as my invention:

1. A furnace comprising, in combination, a circular casing having side and bottom walls and an inwardly extending flange at the top, heat insulating material lining the casing at the sides and bottom, refractory material inside of said heat insulating lining at the sides and bottom, said refractory material extending substantially above said inwardly extending flange, a plurality of openings through said side wall and linings, said openings being inclined inwardly and upwardly and also inclined in the same direction to the radii of said casing, and a burner in each of said openings.

2. A furnace comprising, in combination, a vertical cylindrical casing open at the top, refractory material lining the bottom and peripheral walls of said casing, said peripheral lining extending substantially above the top of said casing, a plurality of openings through said peripheral wall and lining, said openings being inclined inwardly and upwardly and also inclined in the same direction to the radii of said casing, and a burner in each of said openings.

3. The combination with a vertical tubular

boiler having an annular depending water leg, of a cylindrical casing supporting said boiler, said casing comprising a plurality of radial sectors, each sector having a flange at the top, said flange being equal in width to the thickness of said water leg, each sector also having a bottom flange and side flanges, said side flanges extending from said top flange to said bottom flange, a bottom plate supported on said bottom flanges and closing the bottom of said casing, a refractory lining at the bottom and side of said casing, the side lining extending substantially above the top of said casing and into the inner space defined by said water leg, a plurality of peripheral openings through said casing and lining, said openings being inclined inwardly and upwardly and also inclined in the same direction to the radii of said casing, and a burner in each of said openings.

4. A furnace comprising, in combination, a cylindrical casing having side and bottom walls, said casing comprising a plurality of peripheral sectors, each sector having an inwardly extending flange at the top, a refractory lining for the side and bottom walls of the casing, said refractory lining extending substantially above said flanges, a plurality of peripherally spaced openings through said casing and said lining, and a burner in each of said openings.

In testimony whereof, I have hereunto affixed my signature.

CHARLES B. PAGE.
